F. W. ANDREW ET AL

LOCK MECHANISM

Filed June 21, 1926

UNITED STATES PATENT OFFICE.

FREDERICK W. ANDREW, OF ANDALUSIA, PENNSYLVANIA, AND MILTON TIBBETTS, OF DETROIT, MICHIGAN, ASSIGNORS TO FACKARD MOTOR CAR COMPANY, OF DETROIT, MICHIGAN, A CORPORATION OF MICHIGAN.

LOCK MECHANISM.

Application filed June 21, 1926. Serial No. 117,248.

This invention relates to lock mechanism and particularly to combination key and keyless lock mechanism.

One of the objects of the present invention is to provide a lock mechanism that may be released without a key but which, if improperly operated, will run with the mechanism ineffectual.

Another object of the invention is to provide a switch mechanism with both a key and a keyless releasing device.

Another object of the invention is to provide a lock mechanism with a hand release mechanism of novel and efficient construction.

Another object of the invention is to provide a reciprocating lock member with a rotating and reciprocating lock release device which is rendered inoperative upon being improperly manipulated.

Another object of the invention is to provide a lock mechanism with a hand release device which must be rotated to a predetermined position before it will unlock the mechanism and which must be rotated to another position before the mechanism can return to its full unlocked position.

Other objects of the invention will appear from the following description taken in connection with the drawings, which form a part of this specification, and in which:

Fig. 1 is a face view of a lock mechanism embodying the invention;

Fig. 2 is a section substantially on the line 2—2 of Fig. 1 with the switch in its locked position;

Fig. 3 is a section substantially on the line 3—3 of Fig. 2;

Fig. 4 is a section substantially on the line 4—4 of Fig. 2;

Fig. 5 is a sectional view of part of the mechanism shown in Fig. 2 with the release mechanism locked in inoperative position, and

Fig. 6 is a view somewhat similar to Fig. 5 showing the switch in its unlocked position.

Referring to the drawings, 10 indicates the steering column of a motor vehicle and 11 is the instrument board thereof. 12 is a bracket connecting the steering column to the instrument board and forming a support for the lock mechanism thereof. Any suitable means, not shown, for connecting the bracket

to the steering column and instrument board may be employed.

The invention is shown in connection with a reciprocating switch and this switch is indicated generally at 13 in Fig. 2. A plunger 14 is connected to it, and an integral rod or bar 15 extends from the plunger to the switch. A guide piece 16 is mounted in the bracket 12 to surround and guide the plunger 14, and a spring 17 surrounds the rod 15 and yieldingly presses the plunger 14 outwardly towards its on or unlocked position. A pin 18 limits the movement of the plunger 14.

This plunger 14 and the switch of which it is a part forms the member to be locked. It is manually pushed inwardly to its locked position and the spring 17 presses it outwardly to its unlocked position. It is retained in its locked position by a locking bolt 19 operating behind a shoulder 19' and spring pressed to that position as by a spring 20 as shown in Fig. 2. The bolt may be retracted by the ordinary key lock cylinder 21 as shown in Figs. 1 and 2. The plunger may always be unlocked by this key release mechanism. It is shown in its locked position in Figs. 2 and 5 and in its unlocked position in Fig. 6. In this latter position the switch is closed and current for the ignition of the engine is transmitted through a wire 22 in the usual way.

The bolt 19 which forms the device for locking the member 14 may also be released from its locking position by a hand operated mechanism without the use of a key. This mechanism is so constructed that it will release the bolt when it is manipulated in but one of its several positions and when it is manipulated in any other but this one position it is locked out of operation so that thereafter the locking bolt can be released only by means of the key mechanism. In other words, the correct manipulation of this hand release mechanism will operate to release the bolt but the incorrect manipulation of it will render it inoperative.

Also, since it is undesirable to leave the hand release mechanism in its releasing position for the observance of other than the operator, means are provided for requiring the turning of the mechanism to another position before the switch member can move to its full unlocked position.

Suitably mounted in the casing 12 adjacent to the plunger 14 and preferably parallel thereto, is a shaft 23 which may be both rotated and reciprocated. This shaft is provided 5 with a finger piece 24 which has a pointer 25 adapted to co-operate with a dial 26 on the face of the casing. This pointer and dial indicate the position of certain of the parts of the shaft as will be hereinafter described. 10 The finger piece 24 has a bolt 27 extending through the shaft 23, and a large headed screw 28 at the inner end of the bolt 27 operates as a stop for a spring 29 surrounding the inner end of the bolt. There is a splined 15 connection between the outer end of the shaft 23 and the finger piece 24, as at 30, which connection permits angular adjustment of the finger piece and consequently the dial 25, as shown in Fig. 2. This result is accomplished, as seen in Fig. 2, by merely pulling 20 outwardly the finger piece 24, thereby compressing the spring 29 and turning the finger piece relative to the shaft 23 and letting the splined connection drop into a different 25 groove.

The shaft 23 is formed with two separated 30 annular flanges 31 and 32, leaving an annular groove 33 between them. At one point in the circumference of these flanges there is a cam 34 arranged to operate a pivoted dog 35, the latter being pivoted at 36 in the casing or bracket. This dog in a way forms a continuation of the locking bolt 19 since one 35 of its arms 37 rests against the bolt 19 and another of its arms 38 rests on the outer surface of the flange 31. The spring bolt 19, therefore, yieldingly presses the dog 35 against the flange 31 and towards the center of the shaft 23. Thus, if the shaft 23 is 40 pushed inwardly the arm 38 of the dog 35 will drop into the groove 33 of the shaft unless it so happens that the shaft has been rotated to a position where the cam 34 is directly under the arm 38. In that event, 45 the cam 34 will push the dog or lever 35 and rock it on its pivot so that its arm 37 will push the bolt 19 inwardly and release it from the shoulder 19'. The spring 17 will then tend to push the plunger 14 outwardly. 50 However, if the plunger should be moved outwardly to its fully unlocked position with the pointer 25 in the release position of the shaft 23, the pointer would be left in that position and it would be easy for some 55 unauthorized person to note the position of the pointer and then such unauthorized person would be in possession of the lock combination. The plunger 14 therefore is provided with an arm 39 secured to it as by the 60 screws 40, which arm will abut against the flange 31 when the plunger 14 attempts to move outwardly under pressure of the spring 17. The plunger therefore cannot move outwardly without carrying with it the shaft 23 and the shaft 23 is held against outward 65

movement as by means that will now be described.

At the inner end of the shaft 23 is a block 41 which forms a continuation of the shaft and moves with it both in its rotary movement and in its reciprocating movement, except of course when the finger piece is being adjusted relative to the shaft, as explained above. This block 41 has its outer end serrated, as shown particularly at 42 in Fig. 4, 70 and a spring pressed pin 43 operated on these serrations so that the rotation of the shaft may be felt by the operator and the shaft may be advanced around step by step. The inner ends of these serrations are beveled, as shown at 44 in Fig. 2, so that when the shaft 23 is pushed inwardly the pin 43 will ride up on the outer surface of the block and drop into an annular groove 45 in the block. The pin 43 thereafter retains the shaft 23 75 against outward movement until the shaft has been further rotated so that the pin 43 is in line with the longitudinal groove 46 in the block. This groove will then permit the outward movement of the shaft 23 and since the 80 arm 39 of the plunger 14 is pressing outwardly against the flange 31 of the shaft 23, the plunger and the shaft are moved outwardly together with the pointer 25 in a position different from the release position of 85 the cam 34. Preferably the pointer is in the zero position of the dial 26 so that the pointer will always stand at zero position just after it has been manipulated to release the bolt. The inner part of the bolt 27 is 90 square, as shown at 47 in Figs. 2, 3 and 4, and the opening in the block 41 is also square so that the block will turn with the bolt 27 and consequently with the finger piece 24. Thus the block 41, and consequently its longitudinal groove 46, bears a constant relationship to the position of the pointer 25 regardless of the angular adjustment of the finger piece 24 relative to the shaft 23. 100

The shaft 23 is provided with a spring 48 110 which operates against the flange 31 for retracting the shaft. The shaft 23 also is provided with splines 49 between which a pin 50 operates as the shaft is reciprocated. At the ends of the splines 49 are annular 115 grooves 51 and 52 and when the pin 50 is in either of these grooves the shaft 23 may be rotated. However, when the shaft 23 is in an intermediate position, the pin 50 is between two of the splines 49 and consequently 120 the shaft cannot be rotated. The shaft is in this intermediate position when the arm 38 of the lever 35 has dropped into the annular groove 33 of the shaft, and the shaft, therefore, is then locked against both reciprocation and rotation since the arm 38 prevents reciprocation and the pin 50 prevents rotation. The annular groove 51 is provided so that the shaft may be rotated to 125 its correct position for endwise movement to 130

release the bolt, and the annular groove 52 is provided so that the shaft may again be rotated to permit the pin 43 to line up with the groove 46 and the shaft returned to its original position.

In order that the hand release mechanism may be reset after it has been incorrectly manipulated, means are provided for withdrawing the lever 35 from the groove 33 as the plunger 14 is moved to its unlocked position as by the use of the key release mechanism. Thus, the lever 35 has an arm 53 thereon co-operating with an opening 54 in the arm 39 of the plunger. The arm 53 is preferably tapered so that as the plunger 14 moves to its unlocked position, the arm 39 will operate along the tapered part of the arm 53 and positively withdraw the arm 38 from the groove 33 and thereby release the shaft 23 so its spring 48 may return it to its original position.

The operation of the mechanism is as follows: When it is desired to stop the engine of a motor vehicle, the switch is moved to its "off" position by the operator pushing in the plunger 14. As the switch goes off, the locking bolt 19 catches behind the shoulder 19' and retains the plunger and the switch in locked position. The parts are then as shown in Figs. 1 and 2 except that in Fig. 2 the shaft 23, and consequently the pointer 25, have been turned 180°. Assuming that the combination or release number is "6" on the dial 26, in order to release the plunger 14 the finger piece 24, and consequently the shaft 23, may be rotated from zero, as shown in Fig. 1, to 6, as shown in Fig. 2. This brings the cam 34 directly in line with the arm 38 and if the shaft 23 is then pushed inwardly, the cam will operate through the dog 35 to push the locking bolt 19 inwardly until it is released from the shoulder 19'. The spring 17 will then tend to push the plunger 14 outwardly and the arm 39 will abut against the flange 31 of the shaft 23. The pin 43 has entered the groove 45 and the shaft 23 therefore cannot be retracted until its pointer 25 has been manually turned to zero position. When the shaft reaches that position it immediately snaps back into place and the plunger 14 snaps to its fully unlocked position. It is shown in this position in Fig. 6.

Assuming that the parts are as shown in Fig. 2 except that the shaft 23 is in any other angular position, such, for instance, as zero position, one unacquainted with the release number would have but one chance in twelve of guessing the correct number and, if he would not guess the right one the first time, the mechanism would be locked in inoperative position. Thus, suppose the unauthorized person pushed the shaft 23 inwardly with the pointer 25 in zero position. After the start of the inward movement of

the shaft 23, the pin 50 would enter between two of the splines 49 and the shaft could not then be turned to feel for the cam 34. If the shaft is then pushed as much as half way inwardly, the arm 38 will catch in the annular groove 33 and prevent further movement of the shaft. As the arm 38 is pressed into the groove 33 by spring action of the bolt 19, it will stay there and also prevent retraction of the shaft 23. The shaft 23 may therefore neither be pushed in or pulled out, and it is also impossible to rotate it. It is shown in this position in Fig. 5. The hand release mechanism therefore is entirely inoperative and the only way the plunger can be unlocked is by the key mechanism. When the key is applied and the locking bolt 19 withdrawn, the arm 39 of the plunger operates against the lever 35 to withdraw it from the groove 33 and the shaft 23 returns by the action of its spring 48 to its original position.

While we have herein described in some detail a specific embodiment of our invention, which we deem to be new and advantageous and may specifically claim, we do not desire it to be understood that our invention is limited to the exact details of the construction, as it will be apparent that changes may be made therein without departing from the spirit or scope of our invention.

Having thus described our invention, what we claim and desire to secure by Letters Patent is:

1. In a lock mechanism, the combination with a reciprocating switch element and a locking device therefor, of means for releasing the locking device comprising a reciprocating release element and means to prevent turning the release element when the latter has been reciprocated from its inoperative position towards its releasing position.

2. In a lock mechanism, the combination with a switch element spring pressed towards one position, and locking means for holding the element in its other position, of means for releasing said switch element from its locked position comprising an element adapted to be rotated and reciprocated and having a device to release said switch element when said release element is reciprocated with said device in a predetermined position, and means for preventing rotation of the release element immediately after it has been started on its reciprocating movement to release the switch element.

3. In a lock mechanism, the combination with a reciprocating switch element, of a reciprocating release element mounted parallel therewith, a spring pressed transversely operating locking device for the switch element, and means on the release element for moving said device to its inoperative position upon reciprocation of the release ele-

ment with said means in a certain predetermined position.

4. In a lock mechanism, the combination with a locking device, of means to release said locking device comprising a shaft having a high point thereon co-operating with said device to release the latter, a finger piece having a key connection to said shaft, and a bolt extending through said shaft for retaining said finger piece in keyed relation to said shaft.

5. A hand release mechanism for lock devices comprising a shaft having means thereon to release the lock mechanism, a finger piece for said shaft having means for angular adjustment on said shaft, and a bolt extending through said shaft and adapted to retain said finger piece in adjusted position thereon.

6. In a lock release mechanism, the combination with a lock device to be released, of a shaft having means thereon for releasing said device as the shaft is reciprocated, a finger piece at one end of said shaft for rotating and reciprocating the shaft, and a spring surrounding the shaft for returning the latter to its normal inoperative position.

7. In a lock release mechanism, the combination of a lock device to be released, of means for releasing said device comprising a shaft adapted to be rotated and reciprocated, a spring to return said shaft to its normal inoperative position after being reciprocated, and means preventing rotation of said shaft at intermediate points of its reciprocation without interfering with its rotation at both ends of its reciprocating movement.

8. In a lock mechanism, the combination with a member to be locked, spring means for moving said member from its locked to its unlocked position, and a locking device for retaining said member in its locked position, of means for releasing said device comprising a release element adapted to be rotated and reciprocated, and means co-operating with said release element and interconnecting said release element with said member to be locked, so constructed that the release element must first be turned to a predetermined position and then reciprocated to release said device whereby said member is moved towards its unlocked position but is retained by said release element until the latter is turned to another predetermined position.

9. In a lock mechanism, the combination with a member to be locked, a spring for returning said member to its unlocked position, and a locking device for retaining said member in its locked position, of means for releasing said member from locked position comprising a shaft adapted to be rotated and reciprocated, a finger piece for operating the shaft, means on the shaft arranged in prede-

termined and adjustable position angularly relative to said finger piece, said shaft means being adapted to release said device as the shaft is reciprocated, means preventing rotation of the shaft except when it is in one or the other of its extreme positions, means interconnecting the shaft and said member whereby the shaft retains the member against retraction after said device has released said member, and means on the shaft whereby the latter may be returned to its normal inoperative position when rotated to a predetermined angular position.

10. In a lock mechanism, the combination with a reciprocating switch member, a spring pressed laterally operating locking bolt for said member, a release shaft having a high point thereon adapted to co-operate with said locking bolt to release said locking bolt, and means operated by the spring of said bolt for holding the shaft in inoperative position when said shaft is reciprocated with its high point in any but a certain predetermined position.

11. In a lock mechanism, the combination with a reciprocating switch member, a spring pressed laterally operating locking bolt for said member, a release shaft having a high point thereon adapted to co-operate with said locking bolt to release said locking bolt, means operated by the spring of said bolt for holding the shaft in inoperative position when said shaft is reciprocated with its high point in any but a certain predetermined position, and means preventing rotation of the shaft when so held in inoperative position.

12. In a lock mechanism, the combination with a reciprocating switch device, a locking bolt therefor, a bolt release mechanism comprising a reciprocating element having a high point thereon, means adapted to catch and hold said element when reciprocated with its high point in any but a certain predetermined position, and a second release mechanism adapted to release said bolt and reset the first release mechanism.

13. In a lock mechanism, the combination with a member to be locked, a locking bolt therefor, a bolt release mechanism comprising a shaft adapted to be manually rotated and reciprocated, said shaft having two separated annular flanges thereon providing an annular groove between them, and a member arranged between the bolt and said shaft adapted to release the bolt when the shaft is reciprocated in one of its angular positions and adapted to catch in said groove and prevent retraction of the shaft when the shaft is reciprocated in another of its angular positions.

14. In a lock mechanism, the combination with a reciprocating plunger and a locking bolt therein, of a bolt release mechanism, a latch adapted to catch and hold said mechanism when the latter is incorrectly operated,

and means on the plunger for restoring said latch to its inoperative position when the plunger is moved to its unlocked position.

15. In a lock release mechanism, the combination of a shaft having a release cam thereon, means for catching and holding the shaft when the latter is reciprocated in any but its release position, means for catching and holding the shaft when the latter is given a full reciprocation in its releasing position, said latter means acting to retain said shaft against reciprocation until it has been rotated to another predetermined position.
16. In a lock release mechanism, the combination of a shaft adapted to be rotated and reciprocated, said shaft being formed with splines and with an annular groove at each end of the splines, a stationary pin adapted to operate in said grooves and in the spaces

between said splines, thus permitting rotation of the shaft at its extreme positions by preventing rotation at an intermediate position, and a latch for catching and holding the shaft at an intermediate position when the shaft is operated in any but a certain predetermined angular position.

17. In a lock release mechanism, the combination of a shaft adapted to be manually rotated and reciprocated, releasing means on the shaft arranged to operate upon reciprocation of the shaft with the releasing means in a certain angular position, and means to retain said shaft against retraction until the shaft is rotated to another angular position.

In testimony whereof we affix our signatures.

FREDERICK W. ANDREW.
MILTON TIBBETTS.
